DESIGN FOR A FUR SCARF OR SIMILAR ARTICLE

Samuel H. Dick, Brooklyn, N. Y.

Application June 4, 1941, Serial No. 101,273

Term of patent 3½ years

To all whom it may concern:

Be it known that I, Samuel H. Dick, a citizen of the United States, residing in Brooklyn, New York city, in the county of Kings and State of New York, have invented a new, original, and ornamental Design for a Fur Scarf or Similar Article, of which the following is a specification, reference being had to the accompanying drawing, forming part thereof.

Figure 1 is a front view of a fur scarf or similar article, showing my new design; and

I claim:

The ornamental design for a fur scarf or similar article, substantially as shown.

SAMUEL H. DICK.
